MANUFACTURE OF CARBURETED WATER
GAS WITH HEAVY OIL

Owen B. Evans, Philadelphia, Pa., assignor to
The United Gas Improvement Company, Phila-
delphia, Pa., a corporation of Pennsylvania

Application January 21, 1931, Serial No. 510,130

5 Claims. (Cl. 48—208)

The present invention relates to the manufacture of carbureted water gas.

The principal object of the invention is the provision of an improved method of and apparatus for the manufacture of carbureted water gas which is especially adapted to the employment of heavy oils and residuums as the carbureting material.

By heavy oils, I mean to include those oils which when vaporized in the ordinary checker filled carburetor produce excessive carbon deposition on the checker brick and lead to the collection on the checker brick of excessive quantities of ash and fuel from the generator due to 10 deposited pitch from the oil. These heavy oils vary greatly in composition, but those skilled in the art will know what is meant by the term. As an example may be mentioned the so-called "bunker" oils. These may consist of topped 20 crude oils and may contain varying quantities of cracker tar. On vaporization and cracking to produce gas they yield comparatively large quantities of coke as compared with gas oil.

Due to the undue deposition of material in 25 the checkerbrick with consequent stoppage of the gas passages, it is not the best practice to vaporize these heavy oils in the ordinary checker filled carburetor. There are better methods, for instance, vaporizing the oil on the top of the 30 generator fuel bed after the top of the fuel bed has been especially heated by combustion of the producer gas generated by the primary air blast during the blow or vaporizing the oils by spraying them through a nebulizing spray into a 35 checkerless carburetor or the employment of both of these methods.

Whichever is employed, it is a characteristic of these oils that although they require more heat for vaporization than ordinary gas oil, the resultant vapors require less heat for fixing to oil gas.

In ordinary carbureted water gas practice, the producer gas generated in the fuel bed by the primary air blast is burned in passing through the carburetor and superheater in series, with 45 secondary air admitted as the producer gas enters the carburetor. The most intense heating effect is in the top of the carburetor and heat is stored there at the highest temperature. The temperature decreases along the path of the 50 blast gases through the carburetor and superheater.

In the use of ordinary gas oil for the carbureting material, the oil is vaporized during the run (often only during the up run) in the higher 55 temperature heat storage in the top of the car-

buretor and the resultant oil vapors with the water gas traverse the remainder of the carburetor and the superheater in series and are fixed without overcracking.

In the use of heavy oil, however, I have found 5 that the above customary method of operation is unsatisfactory. The securing of a temperature in the portion of the set employed for oil vaporization, high enough to vaporize the oil with sufficient rapidity sets up temperature conditions in the succeeding portions of the set traversed by the blast gases which produce overcracking during the fixing of the oil vapors, if they follow the path of the blast gases. The combination of the temperature and the time of 10 contact with the heated surfaces, the time of contact-temperature effect is excessive.

This overcracking is particularly undesirable where it is desired to produce a water gas tar which is adapted for use in present processes of 20 manufacture of bituminous road material. It is present common practice in the manufacture of road compound to employ water gas tar as a thinning medium for coal gas tar. The water gas tar produced in the use of heavy oil under 25 the above described conditions of overcracking is likely to be heavier than coal gas tar and useless as a thinning medium. As fuel the tar is worth only a fraction of its value as road compound 30 material.

According to the present invention, the producer gas generated by the primary generator air blast during the blow is burned with secondary air and its heat stored. During the up run, a portion of the stored heat at high temperature is employed to vaporize the heavy oil, but instead of passing the resultant oil vapors together with the up run water gas through the length of the heat storage previously traversed by the blast gases, only a portion of this heat storage is utilized for fixing, the oil vapors and up run water gas being by-passed around the remaining portion. Preferably the portion of the heat storage so by-passed is a portion of the path of the blast gases intermediate the vaporizing and fixing surfaces or is in parallel with the path across the fixing surfaces. The heat stored in the portion of the heat storage so by-passed is recuperated by traversing this portion of the heat storage with the down run steam. In case 45 the heat absorbed by the steam is not sufficient to reduce the temperature to the desired point water may be introduced with or without steam to secure further lowering of the temperature. Steam for the down run may also be passed 50

through the portion of the heat storage utilized for fixing.

A further object of the invention is the selective control of the proportionate quantities of heat stored during the blow, in the portion of the heat storage employed for fixing and the portion by-passed by the oil vapors but employed for steam superheating.

The invention will be further described in connection with the attached figures which form a part of this specification and which show forms of the apparatus of the invention chosen for illustration and in which

Fig. 1 shows, in partial elevation and partial vertical cross section, a three shell carbureted water gas set, with oil vaporized on the top of the fuel bed.

Fig. 2 shows, in partial elevation and partial cross section, a three shell carbureted water gas set with oil vaporized in an empty carbureting chamber.

Fig. 3 shows, in partial elevation and partial vertical cross section, a two shell set, with oil vaporized on the top of the fuel bed.

Fig. 4 shows, in partial elevation and partial vertical cross section, a two shell set with oil vaporized on the top of the fuel bed and in an empty carbureting chamber.

Referring to Figure 1,

1 is the generator, 2 the carbureter, 3 the superheater and 4 the wash box of the usual three shell carbureted water gas set. Inasmuch as in this illustration of my invention the carbureter 2 is not employed for carbureting, it will hereafter be referred to as a heat exchanger.

The generator is provided with the ignited fuel bed 5 and with the air supply means 6 and the steam supply means 7 for up air blasting and steaming respectively. The generator is also provided with secondary air supply means for admitting air adjacent the top of the fuel bed, illustrated as marginally below the fuel bed top and as comprising the air supply pipe 8, bustle pipe 9 and connections 10. There is also provision of the oil supply means 11 for delivering oil onto the marginal zone heated by the secondary combustion.

The generator is further provided with the gas offtake 12 which leads by branch pipe 13 and valve 14 to the heat exchanger 2 and by branch pipe 15, valve 16 and connection 17 to the superheater 3. The heat exchanger 2 and superheater 3 are in communication through connection 17.

The superheater is provided with the stack valve 18 and with the gas offtake 19 provided with valve 20 leading to wash box 4.

There is also a gas offtake 21, provided with valve 22, leading from below the generator fuel bed to the wash box. Gas offtake 23 provided with valve 24 leads from the wash box to storage or other disposal. 25 and 26 are means for supplying steam to the superheater 3 and heat exchanger 2, respectively for downrunning.

In operation of the apparatus of Figure 1, with valves 14, 16, 18 and 20 open, the fuel bed is blasted with air supplied through 6. The resultant producer gas is burned with secondary air admitted through 8, 9 and 10 to heat a marginal zone at the top of the fuel bed. The blast gases leaving the generator are divided, a portion passing through connection 13 and the heat exchanger 2 to the superheater 3 and another portion passing through connection 15 to the superheater, by-passing the heat exchanger 2. The blast gases pass through the superheater and issue from the

stack. By controlling the flow through connections 13 and 15, the total heat stored in vessels 2 and 3 may be divided as desired between the two vessels, and a control of temperature conditions in the vessels effected.

5

As an alternative to passing gas simultaneously through connections 13 and 15, valves 14 and 16 may be alternately opened and closed during the blow, alternately passing all the blast gas through both the heat exchanger and the superheater, 10 and alternately by-passing all of the blast gas around the heat exchanger.

After the blow with valves 14, 18 and 22 closed, and valves 16, 19 and 24 open, an uprun is made with steam supplied through 7. The uprun water 15 gas is carbureted by oil admitted through 11 and sprayed onto the marginal hot zone at the top of the fire. The resultant oil vapors and water gas are by-passed around the heat exchanger 2, by way of connection 15, to the superheater 3, where 20 the oil vapors are fixed by the heat stored in the checkerbrick. The resultant carbureted water gas passes through connection 20 to the wash box and thence to storage.

After the uprun, a downrun is made with 25 valves 14, 18 and 20 closed and valves 16, 22 and 24 open. Steam is admitted through 26 to the heat exchanger and the stored heat in the checkerbrick utilized to superheat the steam which passes by way of connection 15 to the top of the 30 generator. Some steam may be admitted also at 25 to the superheater, superheated therein and also passed to the generator by way of connection 15. The steam passes down through the fuel bed, the resultant water gas going to the 35 wash box by way of connection 21 and thence to storage.

After the downrun a short uncarbureted uprun is made as a purge and the cycle repeated.

Referring to Figure 2,

40

27 is the generator provided with the ignited fuel bed 28 and with the air and steam supply means 29 and 30 for up air blasting and steaming, respectively. The generator is further provided with the gas offtake 31 having the branch 45 32 provided with valve 33 and branch 34 provided with valve 35. Connections 32 and 33 lead to the upper and lower portions, respectively, of the carbureting chamber 36 in the combined carbureter and superheater 37. Above the carbureting chamber, vessel 37 is provided with the checkerbrick 38 and is further provided with stack valve 39. 40 is a gas offtake provided with valve 41 leading to the wash box 42. The carbureting chamber is provided with the oil supply means 43, including 55 a nebulizing spray.

50

The carbureting chamber is in communication with the heat exchanger 44, which is provided with checkerbrick 45 and stack valve 46.

The generator below the fuel bed is provided 60 with the gas offtake 47 provided with valve 48 and leading to the wash box. Gas offtake 49 provided with valve 50 leads from the wash box to storage or other disposal.

65

51 and 52 are steam supply means for admitting steam to the heat exchanger 44 and the combined carbureted and superheater 37, respectively. 53 is a supply of secondary air.

In operation with valves 35 and 48 closed and valve 33 open the generator is blasted with air 70 supplied through 28 and the resultant producer gas burned with secondary air admitted through 53. The resultant blast gases pass either upward through the checkerbrick 38 and out of the stack valve 39, stack valve 46 being closed 75

or with the stack valves reversed, the blast gases pass down through the carbureting chamber 36 and through the heat exchanger 44. The blast gases may be passed alternately in the two paths or simultaneously. The desired path of the blast gases will depend on the temperature conditions in the two vessels, the control being effected to store the desired heat in the vessel 37, balance of the heat being stored in the heat exchanger 44.

After the blow an uprun is made with steam admitted through 38. During the uprun valves 33, 39, 46 and 48 are closed and valves 35, 41 and 50 open. The resultant water gas passes through branch connection 34 to the base of the carbureting chamber 36. Oil is sprayed into the chamber from oil supply means 43 in finely divided form and is vaporized, radiant heat being supplied from the lining. The oil vapors and water gas pass upward through the checkerbrick 38 where the oil vapors are fixed, the resultant carbureted water gas passing to storage through offtake 40, wash box 42 and offtake 49.

After the uprun a downrun is made with valves 39, 41 and 46 closed and valves 48 and 50 open. Steam is admitted to the heat exchanger 44 through steam supply 51, superheated in its passage through the checkerbrick 45 and passed to the generator through either connection 34 or 33, depending whether valves 33 and 35 are open or closed, thereby recuperating the heat stored in the heating surfaces not traversed by the oil vapors and gas. Some steam may be also admitted to vessel 37 through 52 and superheated on checkerbrick 38. The steam passes down through the fuel bed, the resultant water gas going by way of connection 47 to the wash box and thence to storage.

After the downrun a short uncarbureted uprun may be made for purging and the cycle repeated.

Referring to Figure 3.

52 is the generator provided with the ignited fuel bed 53, primary air supply means 54 and steam supply means 55 for upward air blasting and running respectively. There is also provided secondary air supply means 56 including bustle pipe 57 and connections 58 for supplying secondary air and oil supply means 59 as described in connection with Figure 1.

The generator is further provided with the gas offtake 60, having the branch connection 61 provided with valve 62 leading to the base and branch connection 63 provided with valve 64 leading to an intermediate portion of superheater 65.

55 Superheater 65 is provided with the stack valve 66 and with the checkerbrick sections 67 and 68 located below and above connection 63, respectively. The superheater is also provided with gas offtake 69 provided with valve 70 leading to wash box 71. Gas offtake 72 provided with valve 73 leads from the wash box to storage or other disposal.

The generator below the fuel bed is provided with gas offtake 74 provided with valve 75 leading from below the fuel bed to the wash box.

65 The superheater is provided with steam supply means 77 and 78 above the checkerbrick sections 67 and 68, respectively, for downrunning.

In operation, with valve 66 open and valve 75 closed, the fuel bed is blasted with air supplied through 54 and the resultant producer gas burned with secondary air admitted through 56 as described in connection with Figure 1. The resultant blast gases are passed through the vessel 65 either through connection 61 or 63, depending on heat conditions in the checkerbrick sections,

valves 62 and 64 being appropriately set. Blast gases pass either through both checkerbrick sections, or pass only through section 68 by-passing section 67, leaving the superheater through stack valve 66.

5 After the blow with valve 66 and valve 62 closed and valves 64, 70 and 73 open, an uprun is made with steam admitted at 55. The resultant water gas is carbureted with oil supplied through 59 as described in connection with Figure 1. The 10 resultant oil vapors and the water gas pass through connection 63 into vessel 65 and up through the upper checkerbrick 68 where the oil vapors are fixed, the resultant carbureted water gas passing through connection 70, the 15 wash box and offtake 72 to storage.

After the uprun a downrun is made with valves 66, 70 and 64 closed and valves 62, 75 and 73 open. Steam is admitted through 76 and passing down through the lower checkerbrick 67 is superheated recuperating the heat in this portion of the heat storage by-passed during the uprun. Some steam may be also admitted through 71 and passed down through the upper checkerbrick section 68. The superheated steam passes 25 through connection 61 and down through the fuel bed, the resultant water gas passing through connection 74 to the wash box and to storage.

After the downrun a short uncarbureted uprun may be made and the cycle repeated. 30

Referring to Figure 4.

71 is the generator provided with the ignited fuel bed 78, air blasting supply means 79, steam supply means 80 for up air blasting and steaming respectively, secondary air supply means 81 including bustle pipe 82 and connections 83 and oil supply means 84 similar to means previously described in connection with Figure 1.

The generator is also provided with gas offtake 85 having branch connection 86 provided with valve 87 and branch connection 88 provided with valve 89. Connection 86 leads to the top and connection 88 to the bottom of empty carbureting chamber 90 in vessel 91. The carbureting chamber is provided with oil supply means 92 including a nebulizing spray. The checkerbrick 93 is arranged above the chamber 91. 94 is a stack valve. 95 is a connection leading from the vessel 91 through valve 96 to the wash box 97. Gas offtake 98 leads through valve 99 to 50 storage.

The generator is provided with the gas offtake 100, having valve 101 and leading from below the fuel bed to the wash box. 102 is a steam supply means to vessel 91 for downrunning. 55

In operation the generator is blasted with primary air and secondary air as described in connection with Figure 1.

During the blow, valves 89 and 94 are open and valves 87 and 101 closed. The blast gases from 60 the generator pass through connection 88 and up through the carbureting chamber 90 and checkerbrick 93 to the stack.

After the blow an uprun is made with steam supplied at 80 and the resultant gas carbureted 65 with oil supplied through 84 to the top of the fuel bed as described in connection with Figure 1. During this uprun valves 87, 96 and 99 are open and valves 89, 94 and 101 are closed. The oil 70 vapors and water gas pass from the generator by way of connection 86 to the vessel 91 and up through the checkerbrick 93, by-passing the greater part of chamber 90. The vapors are fixed in the checkerbrick, the resultant carbu- 75

reted water gas passing through connection 95 to the wash box and to storage.

After this uprun a downrun is made with steam supplied through 102. During the downrun, valves 87, 94 and 96 are closed, and valves 89, 101 and 99 are open. The steam is superheated in passing through the checkerbrick 93 and chamber 90, passes through connection 88 and down through the generator fuel bed, the resultant water gas passes through offtake 100 to the wash box and to storage.

After the downrun a short uncarbureted uprun is made.

After this uprun a blow is made as before followed by a carbureted uprun. During this uprun carbureting oil is supplied through 92 to chamber 90 instead of to the top of the fuel bed. Valves 87, 94 and 101 are closed and valves 89, 96 and 99 open. The uprun water gas passes from the generator to the base of chamber 90 and is carbureted by the oil supplied through 92, the resultant oil vapors pass with the water gas through the checkerbrick 93 where they are fixed, the resultant carbureted water gas passing through connection 95 and the wash box to storage.

After this uprun a downrun and an uncarbureted uprun are made as before and the cycle is repeated.

It will be obvious to those skilled in the art that the particular details of operation and apparatus above described for illustration may be considerably modified. I do not wish to be limited to such details as, for instance, the order of steps in the cycles described. Also, in admitting secondary air to the generator, the admission may be above the top of the fuel bed, instead of below. These and other modifications may be made without departing from the spirit of this invention which is only limited as the appended claims and the prior art may require.

I claim:

1. A process of manufacturing carbureted water gas which includes the following steps: air blasting an ignited fuel bed, burning the blast gases with secondary air introduced marginally adjacent the upper edge of the fuel bed, and dividing the flow of the blast gases and passing them in two streams through two heat exchange vessels thereby controlling the amount of heat stored in each vessel; introducing steam and oil to said fuel bed and vaporizing the oil and carbureting the blue water gas by the heat stored adjacent the upper part of the fuel bed, leading the water gas and the oil vapors so produced in by-pass relation to one of said heat exchange vessels, fixing the oil vapors by the heat stored in the other of said heat exchange vessels, and leading off the gas.

2. A process of manufacturing carbureted water gas which includes the following steps: air blasting an ignited fuel bed, burning the blast gases with secondary air introduced marginally adjacent the upper edge of the fuel bed, and dividing the flow of the blast gases and passing them in two streams through two heat exchange vessels thereby controlling the amount of heat

stored in each vessel; introducing steam and oil to said fuel bed and vaporizing the oil and carbureting the blue water gas by the heat stored adjacent the upper part of the fuel bed, leading the water gas and the oil vapors so produced in by-pass relation to one of said heat exchange vessels, fixing the oil vapors by the heat stored in the other of said heat exchange vessels, and leading off the gas; and making a back run through the fuel bed with steam passed through the by-passed heat exchange vessel and heated by the remaining portion of the heat recovered from the blast gases.

3. In a process of manufacturing carbureted water gas, the following steps: one step being, air blasting an ignited bed of solid fuel, burning the resulting blast gases with secondary air in a combustion space and storing heat therein, and then storing a selectively controlled portion of the remaining heat of said blast gas in a fixing zone; and another step being, steam blasting said fuel bed thereby generating blue water gas, introducing heavy oil directly into the combustion space and carbureting said blue water gas with the vapor resulting from the vaporization of said heavy oil, and fixing said heavy oil vapors in said water gas by means of the heat stored in said fixing zone.

4. In a process of manufacturing carbureted water gas with heavy oil, the following steps: one step being, air blasting an ignited bed of solid fuel, burning the resulting undivided blast gas in a combustion space with secondary air and storing heat in said combustion space, dividing said blast gas into parts and conducting said parts through separate parts of a fixing zone, and selectively controlling the amount of heat stored from said gas in said fixing zone; and another step being, steam blasting said fuel bed thereby generating blue water gas, introducing heavy oil directly into the combustion space and carbureting said blue water gas with the vapor resulting from the vaporization of said heavy oil, and fixing said heavy oil vapors in said water gas by means of the heat stored in said fixing zone.

5. In a process of manufacturing carbureted water gas with heavy oil, the following steps: one step being, air blasting an ignited bed of fuel, leading the resulting blast gas in a path including as a part thereof an empty chamber, burning said blast gas in said empty chamber with secondary air and storing heat from said combustion in said chamber, leading the blast gas from said empty chamber through separate parts of a fixing zone, and selectively controlling the amount of heat from said blast gas stored in the parts of said fixing zone; and another step being, steam blasting said fuel bed thereby generating blue water gas, introducing heavy oil directly into the empty chamber and carbureting said blue water gas with the vapor resulting from the vaporization of said heavy oil, and fixing said heavy oil vapors in said water gas by means of the heat stored in said fixing zone.

OWEN B. EVANS.
